(57) **CLAIM**

The ornamental design for a pasta, as shown and described.

DESCRIPTION

FIG. 1 is a top perspective view of a pasta;

FIG. 2 is a top view thereof;

FIG. 3 is a bottom view thereof;

FIG. 4 is a side view thereof; and,

FIG. 5 is a side view thereof.

The broken lines shown in FIGS. 1-5 illustrate portions of the pasta, that form no part of the claimed design.
